UNITED STATES PATENT OFFICE.

LOREN L. WHITNEY, OF HAMMOND, INDIANA, ASSIGNOR TO AMERICAN STEEL
FOUNDRIES, OF CHICAGO, ILLINOIS, A CORPORATION OF NEW JERSEY.

METHOD OF FORMING A FORGED FULCRUM.

1,335,213.

Specification of Letters Patent. Patented Mar. 30, 1920.

Application filed April 26, 1918. Serial No. 230,987.

To all whom it may concern:

Be it known that I, LOREN L. WHITNEY, a citizen of the United States, residing at Hammond, in the county of Lake and State 5 of Indiana, have invented certain new and useful Improvements in Methods of Forming a Forged Fulcrum, of which the following is a specification.

This invention relates to banded forged 10 fulcrums.

One of the objects of my invention is to improve and simplify the method of making forged fulcrums.

Another object is to provide a forged steel 15 fulcrum adapted to meet the various requirements for successful commercial operation.

Generally speaking, these and other objects are accomplished by employing a method of forming a forged steel fulcrum including first providing a blank, bending the 20 same into the form of two arms connected at one end, and then forming a loop or band for embracing a beam compression member by joining the free ends of said arms.

The invention is illustrated on the accompanying sheets of drawings, in which—

Figure 1 is an edge elevation, and Fig. 2 a plan view of a blank, the ends of which have been beveled;

Fig. 3 is a plan view, and Fig. 4 is a side elevation of the same blank after one end thereof has been given a certain predetermined twist;

Fig. 5 is a plan view, and Fig. 6 is a side elevation of the same blank after the other end has been given a certain predetermined twist;

Fig. 7 is a plan view, and Fig. 8 is a side elevation of the blank after it has been bent 40 at its middle point to form two arms;

Fig. 9 is a plan view, and Fig. 10 a side elevation of the same blank after the points of twist of the arms have been squared a predetermined amount;

Fig. 11 is a plan view, and Fig. 12 a side elevation of the same blank after the free ends of the arms have been welded together to form a band for the reception of the brake beam compression member;

Fig. 13 is a plan view, and Fig. 14 a side elevation of the blank after the seat for the tension rod has been formed;

Fig. 15 is a plan view, and Fig. 16 is a side elevation of the completed fulcrum after

the ferrule has been set in place and the 55 arms punched for the brake lever pivot, the compression member of the brake beam being shown in dotted lines; and

Fig. 17 is a rear view of the banded steel 60 fulcrum.

The various novel features of my invention will be apparent from the following description and drawings and will be particularly pointed out in the appended claims.

In forming my fulcrum a piece of stock 65 in the form of a steel blank 10 is provided, and the ends thereof beveled as at 11 for making a lap joint to be referred to herein-after.

One end 12 of the blank 10 is then given a certain predetermined twist, as 70 shown in Figs. 3 and 4, whereupon the other end 13 of the blank is given a corresponding twist in the opposite direction. Then the

blank is bent at its middle point, as shown 75 in Figs. 7 and 8, to form two parallel arms 14 and 15, the twisted ends 12 and 13 of which are parallel with respect to each other.

The arms 14 and 15 are spaced an amount sufficient for the reception of a 80 brake lever. The arms 14 and 15 at the point of twist form one wall 16 of a band for embracing the compression member of a

brake beam. This wall 16 is next given a more definite straight line shape, as shown 85 in Figs. 9 and 10, whereupon the free ends 12 and 13 of the arms 14 and 15, respectively, are bent into the form of a square loop, and the beveled ends 11 welded together to form

a band for the reception of the brake beam compression member, the rear wall 17 of the 90 band being straight and vertical for engaging the web of the brake beam compression member.

A seat 18 is then formed in the bent portion of the blank for the reception of a brake beam tension member, as shown 95 in Figs. 13 and 14, whereupon the arms 14 and 15, as shown in Figs. 15 and 16, are perforated for the reception of a brake lever pivot pin.

A ferrule 19 is also riveted between the arms 14 and 15 of the fulcrum 100 and is provided with a face 20 for engagement with a tapered key 21, which is driven in between the brake beam compression member 22 and the ferrule 19 for causing the band of a forged steel fulcrum to grip

the compression member in a manner to prevent relative movement between the parts.

By means of this method a forged steel

fulcrum is provided which is adapted to meet the requirements for successful commercial operation.

It is my intention to cover all modifications of the invention falling within the spirit and scope of the following claims.

I claim:—

1. The method of forming a forged fulcrum consisting first in providing a blank, then bending the same into the form of two arms, and then forming a band for embracing a brake beam compression member by joining the free ends of said arms.
2. The method of forming a forged fulcrum consisting first in providing a blank, then beveling its ends, then bending the blank to form two arms, and then forming a band for embracing a brake beam member by joining the beveled ends of said blank.
3. The method of forming a forged fulcrum consisting first in providing a blank, then beveling the ends of said blank, then twisting the ends of said blank in opposite directions, then bending the blank at its middle point to form two arms, and then forming a band for embracing a brake beam member by joining the beveled ends of said arms.
4. The method of forming a forged fulcrum consisting first in providing a blank, then bending the same intermediate its ends to form two arms, then forming a band for embracing a brake beam compression member by joining the free ends of said arms, and then forming a seat in the bent end of

said blank for the reception of a brake beam tension member.

5. The method of forming a forged fulcrum consisting first in providing a blank, then twisting the ends thereof in opposite directions, then bending the blank intermediate its ends in the form of two arms, and then bending portions of the twisted ends of said blank to form a loop for the reception of a brake beam member.

6. The method of forming a forged fulcrum consisting first in providing a blank, bending the same intermediate its ends to form two arms, joining the ends of said arms to form a band for the reception of a brake beam member, and then securing a locking key ferrule to the arms of said fulcrum.

7. The method of forming a forged fulcrum consisting first in providing a blank, beveling the ends thereof, then twisting the ends in opposite directions, then bending the blank intermediate its ends, then bending the twisted ends and joining the beveled portions thereof to form a band for the reception of a brake beam member, then forming a seat for the reception of another brake beam member, and then securing to said arms a key ferrule member.

Signed at Hammond, Indiana, this 23rd day of April, 1918.

LOREN L. WHITNEY.
